Inventor,

Mary M. Gordon

UNITED STATES PATENT OFFICE.

MARY MARGARETE GORDON, OF WASHINGTON, DISTRICT OF COLUMBIA.

DESIGN FOR A BADGE.

SPECIFICATION forming part of Design No. 33,536, dated November 13, 1900.

Application filed October 13, 1900. Serial No. 33,014. Term of patent 7 years.

To all whom it may concern:

Be it known that I, MARY MARGARETE GORDON, a citizen of the United States, residing in the city of Washington, District of Columbia, have invented and produced a new and original Design for Badges, of which the following is a specification, reference being had to the accompanying drawing, forming part thereof.

10 In the drawing the figure is an elevation of a badge, showing my design.

As shown in the drawing, my design consists of a bar of the shape illustrated, from

which is suspended, by means of links connected thereto at each end, a bow-knot of the 15 shape shown in the drawing. The bow-knot and the bar are of contrasting colors.

Having described my invention, what I claim as new, and desire to secure by Letters Patent, is—

20 The design for a badge, as herein shown and described.

MARY MARGARETE GORDON.
